UNITED STATES PATENT OFFICE

ALEXANDER BOYNTON, OF SAN ANTONIO, TEXAS

AUTOMATIC WELL FLOWING DEVICE

Application filed November 30, 1927. Serial No. 236,765.

This invention relates to well flowing apparatus, and it consists in the constructions, combinations and arrangements described and claimed.

5 An object in this as well as affiliated applications, mentioned later, is to provide instrumentalities for regulating the inlet of fluid pressure for the elevation of a liquid column, the particular mode of accomplishment of 10 the object in the present embodiment of the invention being the particular formation of an extremity of what is known as the plunger chamber, it being this formation that causes a throttling of the pressure fluid as the pressure 15 differential increases, all this being so developed in the description to follow.

Another object, and one more specifically elucidating the principle last announced, is to effect the foregoing regulation of the pressure 20 fluid by a reduction or tapering of the upper extremity of the plunger chamber, this tapering constituting an obvious diminution in diameter of the plunger chamber from a point where it joins the parallel walls of the 25 plunger chamber and a certain valve seat respectively.

A still further object of the invention is to provide for the introduction of the largest possible volume of pressure fluid into the column 30 of liquid when the differential pressure is lowest, the particular structural arrangement by which the foregoing object is accomplished, comprising the spaced relationship of one extremity of a spring with the lower 35 end of a bore in the plunger.

Other objects and advantages appear in the following specification, reference being had to the accompanying drawings in which,

Figure 1 is a vertical section illustrating 40 one of the foremost conceptions,

Fig. 2 is a fragmentary sectional view showing a portion of the structure in Fig. 1 to better advantage,

Fig. 3 is a cross section taken on the line 45 3—3 of Fig. 1,

Fig. 4 is an elevation of the plunger or valve element mentioned before,

Fig. 5 is a view on the order of Fig. 1 illustrating the adaptation of the invention to the 50 casing method of raising the liquid,

Fig. 6 is a view similar to Fig. 1 illustrating a slight modification, the arrangement here as well as in Fig. 1 being adaptable to the tubing method of raising the liquid,

Fig. 7 is an elevation of the plunger or 55 valve element used in conjunction with the form of the invention in Fig. 6,

Fig. 8 is a longitudinal section of another modification of the invention, the use of some of the elements of Figs. 1 and 5 being recognized,

Fig. 9 is a fragmentary section of the arrangement in Fig. 8 illustrating important details more minutely,

Fig. 10 is a detail sectional view illustrating 60 a modification wherein the walls of the tapering chamber are made straight by way of variation.

Fig. 11 is a sectional view of a still further 70 modification.

This application introduces one of a series of inventions concerned with the setting in motion and elevating of a column of liquid in a well. The underlying principle of this invention is subject to diversified embodiments 75 all relating to the automatic and timely control of the pressure fluid so that the introduction of the latter into the liquid column is regulated according to need.

It is primarily by constructing a portion of 80 the walls of the plunger chamber on a taper that the foregoing principle is carried out according to the present form of the invention. This taper may comprise straight walls but more desirably is predicated upon a formation struck on the arc of a circle, the center 85 of the radius being located approximately on the same horizontal plane as the upper end of the diminishing chamber.

Reference is first made to Figs. 1 to 4 inclusive. The main body 5 of the valve mechanism has threaded engagement with the adjacent ends of the tubing sections 6. The spring chamber 7, formed in a lateral enlargement of the valve body, has communication at one 90 end with a reduced passage 8 in turn communicating with the conduit of the main body through the intervening outlet port 9.

A valve element 10, otherwise and appropriately known as the differential plunger, is 100

axially movable in a valve chamber. The lower end of the valve chamber has an inserted plug 11 with an inlet bore upon which the plunger rests when idle. The upper end or head of the plunger is beveled at 12. This bevel is intended to contact the beveled seat 13 at the low terminal of the passage 8.

It is upon the chamber-formation between the seat 13 and plunger chamber that the emphasis is herein laid. In Fig. 1, the walls 14 outline what is herein known for want of a better name, as a tapering or diminishing chamber. The specific formation of the walls in Fig. 1 is that of a convexity when viewed from within. The walls are struck on the arc of a circle, the center of which is located at a point on a plane extending through the valve seat 13. The effect is to render the chamber 14 of continuously diminishing area in the direction toward the valve seat.

The term "tapering" has been used to designate this quality but may not be entirely correct as applied to the convexly formed walls of the chamber 14 in Fig. 1. Attention will be directed later to Fig. 10, in which the diminishing chamber is produced by tapering walls.

It seems evident that, all forces to the contrary being excepted, the plunger 10 will gravitate upon the plug 11 by virtue of its own weight. This action will be assisted by a spring 15 in the spring chamber 7 to the extent of the compression of the spring, although it is not the function of the spring to seat the plunger upon the lower seat, but to resist upward movement during periods of increasing differential of pressures and aid downward movement during periods of decreasing differential. The spring has an axial extension 16 extending through the passage 8 and chamber 14 into a bore 17 running along the axis of the plunger 10. It is to be carefully noted that the extremity of the axial extension 16 comes into close proximity with the end of the bore. There is room enough to permit an unimpeded upward movement of the plunger and the admission of a large volume of pressure fluid at a time when most needed, before the spring 15 will exercise its influence in retarding further upward motion of the plunger.

This inevitable motion will be accompanied by a throttling of the by-passing pressure fluid by virtue of the action at base of the bevel 12 in reference to the associated convexity 14. A kindred action must follow regardless of whether the diminishing chamber has walls of a tapering nature or of a convex nature.

Spiral ribs 18 on the periphery of the plunger 10 prevent the plunger from leaning or tilting against the walls of the plunger chamber thus obviating any interference with the flow of pressure fluid that might be occasioned were the plunger allowed uncontrolled

freedom that might permit it to assume positions out of the perpendicular. It is to be observed that these ribs are located on the plunger 10 at the end remote from the bevel 12 thus contributing another factor or avoidance of interference with the fluid pressure control. It is conceivable that the spiral ribs 18 may have a rotating effect upon the plunger by virtue of the by-passing pressure fluid thus inducing even wear of the seat. It is not to be supposed that the rotation of the plunger 10 will be free at all times, particularly in view of the fact that spring pressure is exerted thereupon when the plunger has risen a noticeable distance from the lower seat, but such rotation will be sufficient to permit the plunger to engage the seat 13 at a new place each time.

Fig. 5 illustrates a modification of the invention in Fig. 1 to an extent making it adaptable to what is known as the casing method of raising liquid. According to this arrangement, fluid under pressure is admitted to the tubing string 6, the idea being to discharge the well liquid from the casing (not shown) in which the tubing string is suspended. It is now necessary to close the lower extremity of the plunger chamber by a solid plug 19. The former inlet plug 11 is situated at a point above the inlet 20.

A port 21^a comprises the lateral outlet for the pressure fluid admitted to the plunger chamber by the inlet 20 from the fluid conduit within the valve body. The structure and action is otherwise identical with that described in connection with Fig. 1, and corresponding numerals designate like parts.

Fig. 6 discloses a modification in which, upon comparison with Fig. 1, it is to be observed that the diminishing chamber composed of convex or tapering walls of a portion of the plunger chamber is omitted. A sleeve 21^a is substituted, but the effect of the sleeve is the same as that of the former diminishing chamber for the exposed walls of the sleeve are appropriately struck on the arc of a circle producing the desired convexity. A principle already announced may be repeated here. The exposed walls of the sleeve may comprise a straight tapering formation which straight taper is however, not to be preferred.

Appropriate modifications of the plunger 10 must follow the adaptation of the sleeve 21^a. A reduction in the plunger where it passes through the sleeve produces a neck 23. The lower and heavier end may be identified as the plunger body, while the upper and shorter end may be identified as the head 24. The upper edge of the head is beveled at 12.

Spiral ribs 18 perform the same function in respect to the modified plunger, as they do in respect to the one pictured in Fig. 1. But, now they are located near the upper end of

the plunger and the guiding function is contributed to by the exposed wall of the sleeve 21. This combination is for manufacturing reasons not so desirable as that in Fig. 1, but the illustration in Figs. 6 and 7 makes it plain that the ribs may be produced in the casting or by carefully machining the upper metallic portion of the plunger. In other words, the metal may be cast in proper form or cut away in such manner as to leave the ribs outstanding.

Figs. 8 and 9 embody the volume control means shown by Figs. 1 and 6 in addition thereto a diminishing sleeve of similar contour. The diminishing chamber and diminishing sleeve are to be identified at once. The double provision inaugurates a dual control, and the structure of the differential plunger 28 has necessarily been modified to suit the new arrangement. A number of advantages may be attributed to the dual control. For example, should the wall-surface 22 of the sleeve 21 become worn by the abrasive action of sand or corroded away by chemical action, it is to be supposed that the walls 14 of the diminishing chamber would still be sufficiently perfect to ensure a proper throttling action, or vice versa should the walls 14 of diminishing chamber become out of gauge by such action.

The differential plunger 10 includes the frusto-conical body 28 which merges with the neck 23. The latter is surmounted by the head 24, the upper edge of which is beveled at 12 to coact with the valve seat 13. The dual control occurs within the diminishing sleeve 21 and within the diminishing chamber 14, the walls of which are substantially identical in contour. They are both shown as being convex, although any of the formations previously suggested may be substituted with comparatively similar results.

The operation

is readily understood. One of the outstanding features of this invention, as stated in the beginning, is the provision of a by-passing area between the plunger and wall of the diminishing chamber, the size of which by-passing area changes so that a variable volume of fluid may be passed therethrough when the plunger 10 moves axially of said area. This variable area is so shaped that the available passageway diminishes as the plunger advances upward. All of the modifications herein disclosed are predicated upon a passage of such shape as will produce a diminishing passageway as the plunger advances by virtue of the increasing pressure of by-passing pressure fluid.

The reader must acquire the proper conception of the diminishing chamber 14, the latter term being adapted by virtue of the function. The acquisition of this conception will be aided by a brief description of the

mode of construction of the chamber. By preference, chamber 14 is so constructed that a vertical cross section of the walls of the chamber 14 constitute the arc of a circle, the radius of which is designated 29 and the center 30, Figs. 1, 5 and 8.

For descriptive purposes, the upper radial line 29 is to be regarded as perpendicular to the axis of the plunger chamber, and coinciding with the plane in which the lower and largest part of the valve seat 13 is situated. Now it is imperative that the foregoing arc be struck from a center situated either upon this line or plane, or above it. The effect of thus striking the arc is to produce a convexity of contour continuously widening toward the point of juncture with the plunger chamber proper, or, perhaps more correctly stated, producing a continuously diminishing area from the plunger chamber proper to the point of juncture with the valve seat 13.

To locate the center 30 below the plane 29 would not permit proper control, for then the upper end of the chamber 14 would become somewhat enlarged above the point of greatest stricture or smallest diameter. To locate the center 30 a reasonable distance above this plane would be quite practicable for the resulting struck arc would still have the desirable quality of continuous diminution from the larger extremity to the smaller extremity of the diminishing chamber. What has been said in respect to volume control of the convexly formed wall of the diminishing chamber applies also to a tapering formation but the straight taper is not so accurately efficient. Reverting to the arc-formation, it seems evident that the higher the center 30 is located above the plane 29 the more abrupt will be the walls of the chamber 14, provided radii of the same length are used in both instances. The latter arrangement would produce a quicker throttling of the by-passing pressure fluid upon raising of the plunger 10, and, on the other hand, would provide a more rapid increase of admitted pressure fluid as the plunger recedes from its upper seat 13.

There is another possible variation in the formation of the diminishing chamber. This is illustrated in Fig. 9 merely because of the largeness of the view, and consequently the more available space. The reader may regard the following statement as applying to any of the other modifications. The line 29 is to be identified with the foregoing plane upon which the largest part of the seat 13 is located. The arc, if struck from the center 30 will be rather long and gradual.

Suppose the center to be moved closer and up to the point 31. The resulting arc 32 will be shorter and somewhat more abrupt. But, as stated before, it is also possible to move the center to a point still higher above the line or plane 29 as indicated at 33. In this case the

arc 34 will be quite abrupt making it necessary to extend the plunger chamber up higher or farther before it meets the noticeably shortened diminishing chamber.

5 Figs. 1 and 2 illustrate the simplest form of the invention and in these the operation of the foregoing principle is readily made apparent. The reader must suppose a pressure fluid (air or gas) outside of the tubing string 6. The 10 liquid to be elevated is located inside of the tubing string, this supply being fed into the tubing from the supply in the casing due to pressure in the casing. Conditions becoming right (as fully brought out in preceding patent 15 applications #2 filed May 17, 1927 Serial No. 192,049 and #7 filed October 19, 1927 Serial No. 227,301), the plunger 10 will be raised from its lower seat upon the plug 11 by virtue of the superior fluid pressure seeking to gain an outlet at the port 9 and the conduit of the valve body.

At first the plunger will rise without impediment, except its own weight, the extent of this rising movement being equal to the distance 25 between the lower end of the bore 17 and the end of the spring extension 16. This distance of freedom, designated 35 in Figs. 1 and 2, is exactly the same as the distance 36 between the valve bevel 12 and the beginning 30 of the stricture of the chamber 14.

During periods of no pressure differential the head of the plunger 10 will always be found slightly below the lower end of the diminishing chamber. In other words, a distance 35 equal to 36. This distance, as just explained, represents the free travel of the plunger before it engages the spring. From then on the rising action of the plunger 10 will be opposed by the spring 15, the rapidity 40 with which any given external fluid pressure may cause complete seating of the plunger at the valve seat 13 being subject to wide regulation merely through various spring tensions. These varying spring tensions may 45 be obtained in part as follows:

- 50 1. By screwing down upon the spring chamber plug 40,
2. By lengthening spring shank 16,
3. By substituting a larger spring, and
4. By varying the pitch of the spring coil.

Regulation of the by-passing pressure fluid is accomplished by the formation of the walls 14 of the diminishing chamber acting in conjunction with the spring under compression. The rising of the plunger will cause diminishing admission of the by-passing pressure fluid until a complete seal-off is performed when the plunger engages the seat 13.

60 Identical actions occur in respect to the remaining modifications. In Figs. 8 and 9 (see Fig. 9), the distances marked 36 are each the same as the distance 35 between the adjacent ends of the bore 17 and spring extension 16.

In conclusion, first have reference to Fig. 11. The dual control herein illustrated is a modification of the arrangement in Fig. 1, but more properly a further modification of the structures in Figs. 8 and 9. Parts corresponding with Figs. 8 and 9 are given the same reference numerals without necessarily repeating the description. 70

The inlet plug 11 is now screwed into the large end of the inlet passage 37 of a base plug 38, the latter being so-called because the differential plunger 10 rests thereupon during periods of no differential. The formation of the plunger is decidedly different from any illustrated before. The rounded head 39 rests upon the edge of the inlet passage, which head gradually diminishes as at 40 to a predetermined diameter. The upper edge of the inlet passage constitutes a valve seat. The pendent portion 41 of the plunger gradually enlarges to a head 42. 80

This head, however, stops short of the plug 11 so as to leave the inlet passage unimpeded.

Fluid pressure, entering through the plug 11 and the foregoing chamber which may be identified at 43, expends force both upon the head 42 and the rounded head 39 of the plunger, unseating the latter and permitting passage of the fluid through the plunger chamber. As soon as the pendent portion 41 and the valve end 12 approach the respective strictures 40 and 14, a throttling action upon the pressure fluid will become evident. It is needless to repeat this action because the foregoing description of throttling action is 100 common thereto. 90

In order to provide a specific example of the manufacture of one of the flowing devices the following dimensions of certain important parts are to be observed in this case as well as the following cases: #14, Serial No. 233,480, filed November 15, 1927; #15, Serial No. 234,775, filed November 21, 1927; #16, Serial No. 237,051, filed December 1, 1927; #17, Serial No. 239,137, filed December 10, 1927. Or the same result may be obtained by diminishing the size of the plunger with other dimensions remaining constant. Inversely, smaller volumes of gas may be admitted by enlarging the diameter of the plunger with the diameter of plunger chamber remaining constant. 105

The vital dimension in all instances of the plunger and diminishing chamber, respectively designated 10 and 14 in this case, is the difference of .002" to .010" in diameter between the top of the plunger and the upper part of the chamber 14 just below the seat 13 this on a basis of a diameter of $\frac{1}{16}$ " to $\frac{3}{4}$ " of the said upper part of the diminishing chamber. The diameter of the base of the diminishing chamber at the point just above the top of the plunger in the position shown, should be .025" to .030" greater than the diameter of the top of the diminishing chamber. 115 120 125 130

ber adjoining the seat 13. There should be a difference of .015" to .035" between the diameters of the plunger 10 and the straight-walled portion of the plunger chamber.

5 In the instance of the pressed-in bushings (Figs. 6, 8 and 9) there should be a diameter difference of .002" to .005" between the plunger and the opening when the plunger has reached its uppermost position. The 10 opening through the bushing at its base should be greater in diameter by .025" to .030" than the opening through the top of the bushing.

I claim:—

15 1. A valve comprising a body having a passageway affording communication between the interior and exterior, said passageway including a seat and a portion having the walls struck on the arc of a circle so as to afford a continual change in cross sectional area, and a valve element in the passageway actuated toward a seating position upon said seat by the pressure of fluid travelling in said passageway and in its movement causing a 25 continual change in volume of the fluid bypassing in said portion.

2. A valve comprising a body having a passageway affording communication between the interior and exterior, said passageway 30 having a seat adjoining the outlet and a portion adjacent to the seat having the walls formed on an inwardly inclined arch so as to afford continually changing cross sectional areas, and a valve element operable in the 35 passageway by the pressure of fluid travelling therein to effect a continual volumetric control as the plunger advances in respect to said portion prior to sealing-off upon said seat.

3. A valve comprising a valve casing having a passageway affording communication between the interior and exterior, said passageway including a seat and a portion having convexly formed walls defining a diminishing chamber, and a plunger of which one 45 portion always occupies and is operable in the passageway by force of fluid moving in the passageway and of which another portion is thus movable toward the seat effecting a diminution in volume of the by-passing fluid 50 as the plunger advances in said diminishing chamber prior to sealing off upon the seat.

4. A valve comprising a casing having a passageway affording communication between the interior and exterior, said passageway 55 having a seat adjacent to the outlet and a portion having convexly formed walls defining a diminishing chamber, said portion being located remotely from the valve seat, and a plunger operable in and controlling the 60 passageway during a substantial portion of the movement of the plunger having a formation to engage and seal-off upon the valve seat and a second formation co-acting with the walls of the diminishing chamber to effect a 65 volumetric diminution of by-passing fluid

as the plunger is moved in the direction of the valve seat by the pressure thereon.

5. A valve comprising a casing having a passageway affording communication between the interior and exterior said passageway having a valve seat adjacent to the outlet and having a portion with convexly formed walls defining a chamber of diminishing area in the direction of the valve seat, and a plunger operable in the passageway by the 70 pressure of fluid travelling toward the outlet, said plunger having a head arranged to engage the seat and seal-off the passageway and having a constriction becoming larger in the neighborhood of said chamber of diminishing 75 area co-acting with the walls to effect diminishing volumetric control of the by-passing fluid prior to the engagement of the head with the seat.

6. Apparatus for flowing a well comprising 80 a valve having a body with a passageway affording communication between the interior and exterior, said passageway including a constricted portion and a base plug having a constricted inlet, a valve element operable 85 in the passageway and tending to seat upon the base plug inlet, and a portion pendent from the valve element occupying the constricted inlet and formed to throttle by-passing fluid simultaneously with the throttling 90 of said fluid by the valve element when entering said constricted portion upon raising of the valve element from seating position upon said plug.

7. A valve comprising a body having a 95 conduit and a passageway with a fluid inlet and an outlet communicating with the conduit, there being a valve seat in the passageway adjoining the outlet and a portion the 100 walls of which are struck on the arcs of circles having centers approximately in a plane perpendicular to the axis of the passageway, and a plunger movable in the passageway through said portion to effect a continual volumetric control of the fluid 105 prior to a final sealing-off position upon said valve seat.

8. A valve comprising a body having a conduit and a passageway in communication with the conduit, including a plunger chamber with a bevelled seat and an intermediate diminishing chamber having inwardly arched walls the radii of which originate from centers approximately in the plane of the largest part of the valve seat, and a plunger situated in the plunger chamber having a portion to traverse the diminishing chamber and effect a continual volumetric control of the fluid by which the plunger 120 is actuated, prior to assuming a sealing-off position upon said valve seat.

9. A valve comprising a body having a conduit and a communicating passageway with an outlet, the said passageway including a plunger chamber and a diminishing 125

- chamber having arched walls the curvature of which is determined by radii having centers in a plane either at the end of the diminishing chamber next to the outlet or in proximity thereto in the axial direction of the outlet and a plunger situated in the plunger chamber being movable in the diminishing chamber to effect a continual volumetric control of the fluid actuating the plunger.
10. A valve comprising a body having a conduit and a communicating passageway with an outlet, said passageway including a diminishing chamber having inwardly arched walls, and a plunger operable in the passageway by a flow of fluid toward the outlet, said plunger having a head projectible into the diminishing chamber to effect a continual volumetric control of the fluid.
11. A valve comprising a body having a conduit and a communicating passageway with an outlet, said passageway including a cylindrical plunger chamber and a diminishing chamber merging with the plunger chamber and diminishing toward the outlet, and a plunger operable in and controlling the plunger chamber during a substantial portion of the movement of the plunger, having a straight-walled portion that will perform a throttling action when advanced into the diminishing chamber, situated a determined distance to one side of the merging point of the chambers and representing a distance of free travel before said plunger portion advances into the diminishing chamber to effect a volumetric control of the fluid.
12. A valve comprising a body having a passageway affording communication between the interior and exterior, said passageway including a plurality of curved walls which define diminishing areas, and a plunger situated in the passageway having portions co-acting with said walls to effect a continual volumetric control of fluid flowing through the passageway and said areas.
13. A valve comprising a body having a conduit with a communicating passageway having an inlet and an outlet, said passageway comprising a plunger chamber and a diminishing chamber which diminishes toward the outlet, a throttling plunger operable in and controlling the plunger chamber during a substantial portion of the movement of the plunger, having a head portion to coact with the diminishing chamber, and a formation in the plunger chamber also diminishing toward the outlet and being co-acted with by the body of the plunger, any wearing of the wall surface of said formation being compensated for by the more perfect condition of the walls of the diminishing chamber.
14. A valve comprising a body having a cylindrical plunger chamber merging with a convexly-walled portion and having a seat, a cylindrical plunger movable in said chamber by fluid flowing in the chamber and having a head then advancing over said convexly-walled portion toward said seat, the plunger being smaller in diameter than said chamber, and a rib on the plunger contacting the walls of the plunger chamber and preventing the plunger from leaning while traversing the chamber.
15. A valve comprising a body having a plunger chamber with an inlet and an outlet and a seat adjacent to each, a plunger situated in the chamber engaging one of the seats and having a bore, and a spring having an axial extension fitting in the bore in close proximity with the end of the bore leaving room for a limited unimpeded preliminary movement of the plunger from its seat.
16. The herein described method of effecting the flowing of liquid in a well consisting of imposing artificially and externally compressed fluid under a determined constant pressure upon the well liquid, admitting said fluid to a defined column of the liquid, and continuously throttling said admission of fluid to the column upon the establishment of a predetermined pressure differential between the liquid column and said fluid thus to produce an automatic motivation of said column.
- Signed at San Antonio, in the county of Bexar and State of Texas, this 19th day of Oct., A. D. 1927.
- ALEXANDER BOYNTON.
